UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP CAR.

Application filed May 27, 1922. Serial No. 564,050.

To all whom it may concern:

Be it known that I, ARGYLE CAMPBELL, a citizen of the United States, residing at Chicago, in the county of Cook and State 5 of Illinois, have invented a certain new and useful Improvement in Dump Cars, of which the following is a full, clear, concise, and exact description, reference being had to the accompanying drawings, forming a 10 part of this specification.

This invention relates to improvements in dump cars.

One object of the invention is to provide a strong, durable and relatively inexpensive 15 locking mechanism for gravity drop doors of a dump car and more particularly for drop doors of dump cars of the gondola type.

Another object of the invention is to provide a relatively inexpensive combined door brace and hinge strap which may be readily applied to new or old cars.

A further object of the invention is to provide, in a dump car, a novel and efficient 25 combined floor brace and sealing arrangement at the joint between the car floor and the hinge edge of the door in order to prevent any of the load getting in the crack and preventing full closure of the door there- 30 after.

In the drawings forming a part of this specification, Figure 1 is a side elevation of a portion of a gondola car showing my improvements in connection therewith. Figure 2 is a vertical transverse sectional view 35 corresponding substantially to the section line 2—2 of Figure 1. Figure 3 is a part top plan and part horizontal section of the car shown in Figures 1 and 2 and illustrating more particularly the floor door arrangement and certain details of the side 40 wall construction. Figure 4 is an end elevation, upon a larger scale, of one of the door braces. Figure 5 is a view similar to Figure 3 illustrating another embodiment 45 of the invention. Figure 6 is a transverse vertical sectional view of the car shown in Figure 5, the section corresponding to the line 6—6 of Figure 5. And Figures 7 and 50 8 are detail vertical sectional views corresponding to the section line of Figure 5, Figure 7 looking in the direction of the arrows 7—7 and Figure 8 looking in the direction of the arrows 8—8.

Referring first to the construction illustrated in Figures 1 to 4, inclusive, the gondola car therein shown is provided with channel center sills 10, diaphragms or needle beams 11, 12, wooden side wall 13, pressed side stakes 14, pressed diagonal 60 braces 15, angle side sill 16, longitudinal center floor plank 17, longitudinal side floor strip 18 and a plurality of pivoted drop bottom doors each of which is designated generally by the reference character A. 65 The number of the floor doors will vary in accordance with the requirements of the different railroads but generally there will be four on each side of the car. Only one of such doors is illustrated in detail in the 70 drawings, it being deemed unnecessary to show or describe any of the others, inasmuch as it will be understood that the arrangement is similar for each door.

Each of the doors A, is preferably composed of a plurality of longitudinally extending shiplapped planks 19—19 bound together by U-shaped binding plates 20—20 at each end of the door and further secured by a top strip 21 located centrally, as best 80 shown in Figure 3. On the under side, each door A is preferably braced or strengthened by novel combined braces and hinge straps indicated generally by the reference character B.

Each of said combined braces and hinge straps B is preferably made of an angle iron which can be obtained from stock, the same being secured to the under side of the door with one flange thereof located at the top 90 as indicated at 22 and secured to the under face of the door and with the other right angular flange 23 extending vertically downwardly. At the inner or hinge edge of the door, the upper flange 22 is extended beyond the door edge and bent downwardly for a short distance as indicated at 22^a, thence bent in the form of a circle, as indicated at 22^b around a hinge pin 24, the remainder of the flange being thence doubled 100 back against the section 22^c as indicated at 22^c and thence horizontally beneath the door as indicated at 22^d. The other flange 23 is extended up to the hinge pin and beveled off as indicated at 23^a so that a strong brace 105 is supplied for the flange sections 22^a and 22^c right up to the hinge or pivotal connection. The hinge pins 24 are mounted in hinge

butts 25 which are riveted in the upper corners of the corresponding channel center sill 10, as shown in Figure 2.

At the free edges of the door, the braces B 5 are extended beyond the edge of the door and downwardly bent for a slight distance as indicated at B'. At a point approximately directly below the free edge of the door, the depending flange 23 of the brace is bent out of 10 the main plane of said flange 23 in a more or less horizontal direction as indicated at 23^b so that, looking at the end of the brace B, it has the form more or less of a channel cross section, as clearly indicated in Figure 15 4. The flange section 23^b is preferably curved on a radius about a center which is located above the door so as to cooperate with a correspondingly curved supporting shoulder 26 on a pivoted latch 27. The latter is pivotally 20 supported on the outer face of the car side wall as indicated at 28 in a casting 29. The latch 27 may be held in locked or operative position by a cam plate 30 also pivotally supported in the casting 29 at the point 31. 25 As best shown in Figure 1, the pivotal support 28 is located to one side of a vertical line passing through the flange section 23^b and to that side of said vertical line which will cause the curved shoulder 26, as it encages the correspondingly curved flange section 23^b, to wedge against the latter and thus 30 forcibly elevate the door to fully closed position. By forming the brace B at its outer end as above described, it will be observed 35 that I obtain a very strong section, inasmuch as I retain a part of the vertical web 23 as a compression element in sustaining the load on the door and thus eliminate or at least minimize tendency of the flange section 23^b 40 to give or bend under load as it might otherwise do. In actual practice, there will preferably be two of the combined braces and hinge straps B for each door and two corresponding pivoted gravity latches cooperable with the outer extended ends thereof. 45

In the gondola car shown in Figures 1, 2 and 3, the same is of the type known as composite and the doors are relatively wide, extending substantially from the center sill 50 to the plane of the side wall. With doors of such width, it is inadvisable to allow them to fall to a depending vertical position on account of interference with the rail and consequently I have shown stop plates 32 55 secured to the needle beams 11 and 12 which will limit the opening movement of the doors. Preferably also I employ a longitudinally extending cover plate 33 secured to the center plank 17 and extended a slight distance 60 beyond the free edge thereof over the joint between the door and the plank to prevent as much as possible, any of the load getting in the cracks. A similar cover plate 34 may be employed along the free edges of the 65 doors, as clearly shown in Figure 2.

Referring next to the construction illustrated in Figures 5 to 8 inclusive, the gondola car therein shown is of the all steel type, the same having center sills 110, transverse needle beams 111 and 112, side wall 113, side stakes 114, angle side sills 116, and longitudinally extending center cover plate 117 over the center sills. In this form of gondola car, the width of the doors is made considerably less than in the composite type, 70 there being a floor section 40 extending from the center sill about one-third of the distance toward the side wall of the car. The floor doors are indicated at A', the same being relatively narrow and having their 75 free edges engaging beneath the horizontally extending flange of the side sill 116, as best shown in Figure 6. Each of the doors A' is preferably provided with a combined brace and hinge strap B² formed in the 80 same manner as the corresponding door member B, heretofore described. In this connection, it will be observed from examination of Figure 6, that the outer end B³ of each brace B² is deflected downwardly a 85 much greater extent than in the construction heretofore described in order to pass below the side wall of the car, which is extended below the level of the floor. The outer end of the brace B² is formed in the 90 same manner as the outer end of the braces B and similar latches are adapted to cooperate therewith and need not be redescribed. 95

In order to brace the longitudinally extending outer edges of the floor plates 40 100 where the doors are hinged thereto, between the needle beams 111 and 112, I secure to each floor plate 40, a Z-bar 41, having its upper flange 42 extended outwardly, that is, toward the door opening, and the lower 105 flange 43 extended in the opposite direction or inwardly toward the center sill. Each Z-bar 41 extends substantially from needle beam to needle beam and has secured thereto at each end, complementary hinge butt castings C. Said castings C are made right and left and it will only be necessary to describe one of them in detail. 110

Referring more particularly to Figures 6, 7 and 8, each of said castings C is formed 115 at its end with a flange 44 extending in a vertical plane transversely of the car and adapted to be directly riveted to the corresponding needle beam 111 or 112, it being understood that said flange 44 extends across 120 the end of the Z-bar 41. Each casting C is further provided with a horizontally extending flange 45 located beneath and secured to the bottom flange 43 of the Z-bar and with a further vertical flange 46 overlapping and riveted to the web of the Z-bar. 125

At the inner end of each casting C, that is, the end removed from the corresponding needle beam to which it is secured at its other end, each casting C is provided with a pair 130

of spaced vertical flanges 47—47 which are extended upwardly to a point beneath the Z-bar flange 42 and free edge of the floor plate 40, as best indicated in Figures 6 and 5 7. Said spaced flanges 47 are suitably reinforced by edge ribs 46^a and together provide pivotal supports for a hinge pin 126.

Each of the doors A', as previously described, is preferably made of sheet metal 10 and to insure the necessary strength, each door has a depending flange around each edge thereof. Along its hinge edge, said flange, indicated at 48, is slightly indented as indicated at 48^a to clear the free edge of 15 the Z-bar flange 42 and thence is curved on a radius concentric with the hinge pins 126. When the door is in closed position, as shown in Figure 6, it is evident that a comparatively tight seal is obtained between the 20 hinge edge of the door and the floor plate 40 and furthermore, as the door swings to its fully open position, the curved flange 48 and Z-bar flange 42 will maintain their tangential relation, thus preventing any of the load 25 getting in between the door and fixed part of the car and insuring easy closing of the door.

In the arrangement shown in Figures 5 to 30 8, on account of the door being comparatively narrow, the same may be allowed to swing to a depending vertical position as indicated by dotted lines in Figure 6, the door clearing the rail, a portion of the latter being indicated conventionally. This allows 35 of 100% door opening and easy discharge as will be understood by those skilled in the art.

One advantage of the combined floor brace 40 and hinge butt structure just described resides in the fact that the castings C may be made of standard patterns and combined with a Z-bar for any car, regardless of the distance between the needle beams or 45 diaphragms, inasmuch as the Z-bar may obviously be cut to any desired length so that the castings C can always be riveted directly to the needle beams. This is of considerable 50 advantage over braces of the ordinary cast type which require separate patterns for cars having different spacing between needle beams.

I claim:

1. In a dump car having a pivoted gravity drop door, the combination with a brace 55 secured to the under side of the door and extended outwardly beyond the free edge thereof, said brace, at its outer end, having a top flange parallel to the plane of the door, a web perpendicular to the plane of the door, and a 60 bottom flange substantially parallel to the plane of the door; of a hook latch pivoted to swing in a plane substantially perpendicular to the plane of the door when closed and adapted to engage under said bottom flange 65 of the brace.

2. In a dump car having a pivoted gravity drop door, the combination with a brace secured to the under side of the door and extended outwardly beyond the free edge thereof, said brace being of angular cross section 70 beneath the door and of approximately channel cross section at its extended end; of a latch pivoted to the car body adapted to engage under said extended end of the brace to hold the door in closed position. 75

3. In a dump car having a pivoted discharge door, the combination with a brace secured to the underside of the door and extended outwardly beyond an edge thereof, said brace, at its extended end, being of approximately channel cross section with one of the flanges thereof slightly curved; of a latch pivoted to the car body, said latch having an approximately right angled shoulder, one face of which is curved to engage 85 said curved flange of the extended end of the brace.

4. In a dump car having a flat floor section and a pivoted discharge door in approximate alignment with said floor when in closed position, the combination with a combined brace and hinge strap of angular cross section secured to the door, one flange of said brace being secured to the under face of the door and extended beyond the pivoted edge thereof and inclined downwardly from the plane of the door, then bent back upon itself to a point beneath and secured to the door, the other flange being disposed perpendicular to the door; of a pivot pin extended through 100 the doubled-over portion of said brace flange and by which the door is adapted to be hinged to the car body, said pivot pin being secured to the car body below the floor and inwardly of the outer edge thereof. 105

5. In a dump car having a flat floor section and a pivoted discharge door in approximate alignment with said floor when in closed position, the combination with a combined brace and hinge strap secured to the door, said brace and strap being of angular cross section throughout the greater portion of its length with one flange secured to the under side of the door and the other perpendicular thereto, said flange secured to the door being extended beyond the pivoted edge of the door and doubled back upon itself and the other flange terminating adjacent the bend in said doubled-over flange; of means 110 for pivotally connecting said strap to a fixed part of the car body, at a point below the under surface of the door and said floor, and inwardly of the outer edge of the latter. 115

6. In a dump car having a floor with a door opening therein, the combination with 120 a door hinged to swing about an axis disposed beneath and inwardly of an edge of said floor, said door having a rounded edge substantially concentric with said axis and adapted to remain substantially tangent to 130

the under side of the floor edge, in all positions of the door, the planes of the upper surfaces of the door, when in closed position, and said floor substantially co-inciding; 5 of a combined brace and hinge strap secured to said door, said brace and strap being of angular cross section throughout the greater portion of its length, with one flange secured to the under side of the door and the other 10 flange perpendicular thereto, said first named flange being extended beyond the pivoted edge of the door and doubled back on itself, said doubled portion being concentric with said rounded edge; a pivot pin extending 15 through the doubled portion of said brace and by which the door is adapted to be hinged; and means for holding the door in closed position.

7. In a dump car having a floor with a 20 door opening therein, the combination with a door adapted to close said opening and hinged to the car body to swing about an axis beneath one edge of the floor, said door having a rounded edge substantially 25 concentric with said axis; of a longitudinally extending floor brace secured to said edge of the floor on the under side thereof, said brace being of Z-cross section with one flange extended toward the door opening and secured 30 to the floor and the other flange extended away from the door opening, said rounded edge of the door remaining substantially tangent to said first mentioned flange of the brace in all positions of the door.

35 8. In a dump car having a floor with a door opening therein, the combination with a Z-brace secured to the under side of said floor and extending along one edge of the door opening; of a pair of cast hinge butts 40 secured to said brace; and a door adapted to close said opening and pivoted to said butts, said door having a rounded edge substantially concentric with its axis of pivotal movement.

45 9. As an article of manufacture, a floor brace for cars, said brace comprising a section of a commercially rolled shape and two hinge butt castings secured to said shape, said castings having separate means thereon 50 for attaching the same to underframe elements of a car body.

55 10. As an article of manufacture, a combined floor brace and hinge butt comprising, an intermediate section of Z-cross section and two end castings secured to said Z-section, each of said end castings having a hinge 60 butt proper secured to two of the angularly disposed portions of said Z-section and an end flange by which the same may be secured to an element of the car underframe.

65 11. In a dump car having a floor with a door opening therein, the combination with a brace secured to the car floor adjacent the door opening and extending parallel therewith, said brace being of substantially Z-

70 cross section; of a door pivotally attached to said brace, said door having braces on the under side thereof extended outwardly beyond the free edge of the door, said door braces being of angular cross section beneath the door proper and of approximately channel cross section at their outer ends; and pivoted latches cooperable with the extended ends of said door braces to hold the door in closed position.

75 12. In a dump car of the gondola type having a floor with a door opening therein, the combination with a brace secured to the under side of the floor adjacent one edge of the door opening, said floor brace comprising a section of Z-bar and end hinge butt castings secured to the Z-bar; of a floor door having its hinge edge rounded and adapted to remain substantially tangent to one flange of the Z-bar in all positions of the door; combined door braces and hinge straps secured to the under side of the door and by which it is pivoted to said floor brace, said door braces being extended beyond the free edge of the door; and means cooperable with the 80 extended ends of said floor braces for holding the door in closed position.

85 13. In a dump car of the gondola type having a floor with a door opening therein, the combination with a floor brace extending parallel to one edge of the door opening, said floor brace comprising a section of Z-bar and end hinge butt castings secured to the Z-bar; of a floor door having a rounded 90 flange extending along its hinge edge; combined braces and hinge straps secured to the under side of said door, each of said combined door braces and hinge straps being of angular cross section beneath the door proper and extended outwardly beyond the 95 free edge of the door, the extended ends of said door braces being of approximately channel cross section; and latches pivotally secured to the side wall structure of the car and cooperable with said extended ends of 100 the door braces to hold the door in closed position.

105 14. In a dump car having a pivoted gravity drop door, the combination with a brace secured to the under side of the door and extended outwardly beyond an edge thereof, said brace being of substantially angular cross section beneath the door and of approximately channel cross section at its extended end; of supporting means pivoted to the car body adapted to engage under said extended end of the brace to hold the door in closed position.

110 15. As an article of manufacture, a brace for cars, said brace comprising a section of 125 commercially rolled shape and two end castings rigidly secured to said section at the opposite ends thereof, said end castings having means thereon, extending across the ends of said section, for attaching the castings to 130

fixed elements of the car body extended transversely to the direction of the brace.

16. In a dump car having a floor, side wall and side sill depending below the level of the floor, the combination with a floor door pivoted to swing about an axis parallel with the side sill and located an appreciable distance from the center sill of the car, the free edge of the door, in closed position, terminating inside the inner plane of the side wall; of an arm secured to the under side of the door and extended downwardly and outwardly from the free edge thereof to a point below and beyond the outer plane of the side sill; and means located outwardly of the outer plane of the side sill, cooperable with said arm to hold the door in closed position, said door being adapted to fall to a depending position and with the said extended arm therefrom clear of the rail.
17. In a dump car having a floor and side wall, the combination with a floor door pivoted to swing about an axis parallel with the side wall; of an arm secured to the under side of the door and extended outwardly from the free edge thereof, said extended portion of said arm being bent downwardly at an angle to the major portion thereof and terminating in a reversely bent outer end portion, the distance from the pivoted axis of the door to the outer end of the arm being less than the distance between said pivoted axis and the nearest rail; and means cooperable with said outer end portion of said arm to hold the door in closed position.
18. In a dump car having a floor, side wall, and side sill depending below the level

of the floor, the combination with a floor door pivoted to swing about an axis parallel with the side sill; of an arm of angular cross-section with the flanges thereof perpendicular to each other and extending from end to end of said arm, one of said flanges being secured to the under side of the door and said arm being bent downwardly and outwardly from the free edge of said door; and means cooperable with the outer end portion of said arm to hold the door in closed position.

19. In a dump car having a floor, side wall, center sill and a side sill depending below the level of the floor, the combination with a floor door pivoted to swing about an axis parallel with the center sill and located an appreciable distance laterally from the center sill, the free edge of the door, in closed position, terminating inside the inner plane of the side wall; of means for holding the door in closed position, including an extension from the free edge thereof, the distance from the pivotal axis of the door to the outer end of said extension being less than the distance between said pivotal axis and the nearest rail, whereby said door is adapted to fall to a depending position with the extension clear of the rail.

In witness that I claim the foregoing I have hereunto subscribed my name this 22nd day of May, 1922.

ARGYLE CAMPBELL.
